ROBERT GRAY, OF LITCHFIELD, ILLINOIS.

Letters Patent No. 66,702, dated July 16, 1867.

IMPROVEMENT IN ELLIPTIC SPRINGS.

The Schedule referred to in these Letters Patent and making part of the same.

TO ALL WHOM IT MAY CONCERN:

Be it known that I, ROBERT GRAY, of Litchfield, in the county of Montgomery, and State of Illinois, have invented a new and useful Improvement in Corrugated or Ribbed Springs; and I do hereby declare that the following is a full and clear description thereof, reference being had to the accompanying drawings, and to the letters of reference marked thereon.

This invention consists in forming each of the leaves of a spring into a longitudinal corrugation, the said corrugations being so arranged and fitted together in the different leaves as to greatly strengthen the spring, and at the same time to increase its elasticity. The shape of the corrugations, as represented on the faces of the spring leaves, will be nearly or quite parabolic, with convex contour at the ends of said corrugations. The general form of the corrugations, in elevation, is such that the varying lengths of leaves which go to make up the spring will fit nicely together, that is, a long one upon a short one, and *vice versa*.

To enable those skilled in the art to make and use my improved spring, I will proceed to describe its construction and operation.

Figure 1 of the drawings is a side elevation of one of the improved springs, the dotted lines showing corrugation of one leaf entering the thickness of another.

Figure 2 is a side elevation of one leaf.

Figure 3 is a plan of one leaf.

Figure 4 is a transverse section bisecting one leaf.

This spring may be elliptical in its formation, or it may be a semi-ellipse, as is represented by the spring A in the drawings. This latter variety is the more common for locomotives and other similar heavy purposes. The spring A is made up of a number of leaves *a* in the same manner as springs now in use. In each of these leaves there is a corrugation or longitudinal rib *a'*, projecting outwardly from the convex side of the leaf, and nearly its entire length. These corrugations or ribs are to be pressed or rolled out of the solid metal of which the leaf is formed, and in such a manner as to make the width and projection of the rib much larger and stiffer in the centre (longitudinally) of the leaf than toward the ends. This arrangement forms the horizontal projection of the base of the rib, nearly or quite in a parabolic curve, as seen clearly in fig. 3. At the ends of the ribs *a'*, where the two parabolic curves meet, they should be connected by an easy curve, as is also shown in fig. 3. The ribs should not extend the whole length of the leaf, but stop short of the hanger-seat of the long leaves, but approach more nearly to the ends of the shorter ones. The whole construction should be such that the convex side of one rib will fit into the concave side of another. The widening of the rib in its centre gives it a corresponding increase of depth and consequently of strength at that point, and from the centre of each spring thus constructed to its ends there is an increasing elasticity. Springs may be constructed in this manner much more cheaply, both as regards material used and labor required for the manufacture, and the springs so constructed will also be much more elastic and also more durable. A band, B, may be used, as formerly, to connect the different leaves together into the form of a spring.

Having described my invention, what I claim is—

Projecting a rib, *a'*, from the convex side of a leaf of the spring, so as to form a rounded parabolic curve or elliptical curve, as shown in fig. 3, and substantially for the purpose set forth.

ROBERT GRAY.
